UNITED STATES PATENT OFFICE.

GEORGE WASHINGTON GETSINGER, OF SAVANNAH, GEORGIA.

WINDOW-SCREEN MOUNTING.

Application filed June 29, 1921. Serial No. 481,289.

To all whom it may concern:

Be it known that I, GEORGE W. GETSINGER, a citizen of the United States, and a resident of Savannah, in the county of 5 Chatham and State of Georgia, have invented certain new and useful Improvements in Window-Screen Mountings, of which the following is a specification.

This invention relates to a window screen 10 mounting and particularly for screen of the telescopic or folding type.

The object of the invention is to provide a screen mounting means of the above character whereby a screen will be continuously 15 held for fully closing the window opening with which the screen may be associated.

It is also an object of the invention that the mounting means permit the screen to be easily lowered or raised.

20 Other objects relating to details of construction, combination and arrangement of parts will hereinafter appear in the detail description to follow.

The invention is illustrated by way of 25 example in the accompanying drawings, in which—

Figure 1 is an inside elevation of a window casing or frame to which the present invention has been applied.

30 Figure 2 is a detail perspective view illustrating the manner in which the screen may be locked against upward or downward movement.

Figure 3 is a vertical sectional view 35 taken through one of the channel members or guideways of the present invention and showing the manner in which the screen is distended.

Figure 4 is a detailed horizontal sectional 40 view through the one side of window casing with screen in position.

Referring to the drawings more particularly, A indicates generally a casing or frame of a window; 10 the bottom sill; 11 45 the sides of the window frame; 12 the lower sash and 13 the upper sash.

A popular form of metal screens of the telescopic type has a frame composed of members substantially channel shaped in 50 cross section.

In carrying out the present invention, a pair of guideway members 14 which are U-shaped in cross section, as shown in Figure 4, are secured to the inner strip 15 55 which forms the one side of the lower sash 12, by the means of screws as indicated at

16, said screws extending through the bridge portion of the guideways, as shown. Upon the inner side wall 17 of each guideway 14 there is pivoted a pair of finger 60 springs 18, said finger springs consisting of a continuous wire as shown and its intermediate portion wound about a screw bolt 19 which is secured to the inside wall 17 of the guide members 14. Upon the 65 outer and free end of each finger spring 18 there is journaled a roller 20, said rollers extending transversely of the guideways, as shown.

In obtaining the advantages of the present invention a telescopic metal screen generally indicated by the reference numeral B and of the construction heretofore referred to is utilized. As before stated the frame members of the screen are substantially channel-shaped in cross section and are adapted to slide within the guide members 14. In Figure 4 the reference numeral 70 21 indicates the side frame members of the screen B, which as shown, are of the shape 75 stated and the one side of the channel members supporting the screen fabric 22. It is of course to be understood that the top and bottom frame members of the screen are telescopic and constructed in the usual 80 manner. The bridge portion 22' of the channel members 21 are adapted to freely slide within the guideways 14, and the rollers 20 carried by the finger springs 18 85 are adapted to engage thereupon. 90

As is obvious the action of the finger spring 18 is to distend the screen B so that the sides of its frame will continuously engage with the bottom of the guideways 14. The rollers 20 will permit easy upward and 95 downward movement of the screen B and also hold the screen in any raised position desired.

Referring to Figure 2, it will be seen, that a latch member generally indicated at 100 23 is pivotally secured by the pin 24 to the bottom sill 10 and having an offset portion 25, which is adapted to engage upon the base portion 26 of the screen frame. As is 105 obvious by the use of this latch the screen B may be held from upward or downward movement and from the fact that the same cannot be removed from its mounting unless lifted upwardly and out of the guide members 14, the latch 23 provides a means 110 whereby telescopic screens of the character herein shown and described may be locked

against removal by anyone upon the outside of the building with which the screens may be associated.

While I have shown and described the preferred form of my invention it is to be understood that I am aware of the fact that the construction, combination and arrangement of parts may be changed by those skilled in the art without departing from the spirit of my invention, as indicated by the appended claims.

I claim:—

1. In combination an extensible screen, a pair of guideways adapted to slidingly accommodate the side frame members of said screen, and means carried by the window frame for holding the side frame members of the screen in continuous engagement with the bottoms of said guideways, and said means being adapted to permit the vertical movement of said screen.

2. In combination with a telescopic screen of the character described having substantially channel shaped side frame members, a pair of guideways secured in a window frame, one upon each side thereof and adapted to slidingly receive the side frame members of said screen, and spring means carried by the window frame for holding the sections of said telescopic screen against telescopic movement.

3. In combination with a telescopic screen of the character described, having substantially channel shaped side frame members, a pair of guideways secured in a window frame, one upon each side thereof and adapted to slidingly receive the side frame members of said screen, a pair of resilient

ingers carried by each of said guideways and adapted to engage the bridge portion 40 of the respective channel member of said screen frame and hold the said members against telescopic movement.

4. In combination with a telescopic screen of the character described, having substantially channel shaped side frame members, a pair of guideways secured in a window frame, one upon each side thereof and adapted to slidingly receive the side frame members of said screen, a pair of resilient 50 fingers carried by each of said guideways and adapted to engage the bridge portion of the respective channel member of said screen frame and hold the said members against telescopic movement, and a roller carried 55 upon the outer end of each resilient finger adapted to permit vertical movement of said screen.

5. In combination with a telescopic screen of the character described, having substantially channel shaped side frame members, a pair of guideways secured in a window frame, one upon each side thereof and adapted to slidingly receive the side frame members of said screen, a pair of resilient 60 fingers carried by each of said guideways and adapted to engage the bridge portion of the respective channel member of said screen frame and hold the said members against telescopic movement, and latch means by 65 which the screen may be locked against upward movement within said guideways.

GEORGE WASHINGTON GETSINGER.
